UNITED STATES PATENT OFFICE.

OTTO CARLSON, OF ASTORIA, OREGON.

BOAT-HANDLING APPARATUS.

1,283,397.

Specification of Letters Patent.

Patented Oct. 29, 1918.

Application filed March 13, 1918. Serial No. 222,201.

To all whom it may concern:

Be it known that I, OTTO CARLSON, a citizen of the United States, residing at Astoria, in the county of Clatsop and State of Oregon, have invented certain new and useful Improvements in Boat-Handling Apparatus, of which the following is a specification.

My invention relates to improvements in boat handling apparatus for lowering and raising a boat to and from the water, in a highly expeditious manner.

An important object of the invention is to provide an apparatus of the above mentioned character, which is especially useful on ships, where it is required to frequently launch a small boat or dory from the vessel.

A further object of the invention is to provide an apparatus of the above mentioned character, which may be operated for attachment, from within the boat, by one man.

A further object of the invention is to provide an apparatus of the above mentioned character, which when installed in a dory or small boat, automatically releases the boat from the ship's tackle, upon the boat contacting with the water.

Other objects and advantages of the invention will be apparent during the course of the following description.

In the accompanying drawing forming a part of this specification and in which like numerals are employed to designate like parts throughout the same,

Figure 1 is a central vertical longitudinal sectional view through the hull of a boat, having my apparatus attached thereto,

Fig. 2 is a side elevation of a releasing device secured within the hull of a boat, and,

Fig. 3 is a similar view of an attaching device secured within the hull of a boat.

In the drawings wherein for the purpose of illustration is shown a preferred embodiment of my invention, the numeral 5 designates the hull of a boat having a keel 6.

Vertical standards 7, comprised in an attaching apparatus, are disposed within the hull 5, and adjacent the ends thereof. Said standards pass through apertures in the keel 6, and are rigidly secured thereto, by nuts

8. Any other suitable means may be employed to attach the standards 7 to the keel 6 or hull 5. The standards 7 are provided at their upper ends with apertured knuckles 9, receiving pins 9', having knuckles 10' of

U-shaped links 10, pivoted thereon. The U-shaped links are adapted to swing downwardly, in the direction of the arrows. These links 10 have counterweights 10".

Vertical standards 11, comprised in a boat attaching apparatus, are disposed within the hull 5, as shown. Apertures 12, are provided in the keel 6, to receive the lower ends of the standards 11 which are rigidly secured to the keel 6, by nuts 13. Provided on the upper end of the standards 11, are oppositely arranged attaching devices or sockets 14, comprising outwardly extending arms 15 and 15', having overlapping leaf springs 16, attached to the ends thereof.

Disposed midway of the standards 11, are retractile coil springs 17, in screw-threaded engagement with screw-threaded openings 18" of plates 18. The opposite ends of the spring 17 contact with and are rigidly secured to plates 19, which are bolted to the inner plates 18, as at 20. The plates 19 are carried by the standard sections, as shown. The springs 17, provided as part of the attaching device, serve to relieve the boat and apparatus of any undue strain while being raised.

Extending from the ship's davits is tackle 21, carrying a rod 22, which is adapted to engage with the releasing or attaching apparatuses. The rod 22, is curved at its ends as at 23.

When it is desired to launch the boat, the U-shaped links 10, of the standards 7, are placed upon the rod 22 and the boat lowered to the water in the usual manner. Upon contacting with the water, the weight of the boat is relieved from the rod 22 and the links 10, swing out of engagement therewith, as indicated by its arrows, thus leaving the boat free from the tackle. When it is desired to hoist the dory aboard ship, one man standing in the center of the dory may grasp the rod 22 and thrust the ends 100 of the same transversely into the sockets 14, such rod forcing the springs 16 inwardly, to pass the same, and being subsequently held in the sockets by these springs.

It is obvious that the dory may now be raised to the ship's deck.

While I have shown and described the preferred embodiment of my invention, it is understood that I may make such minor changes in arrangement and construction of parts as will remain within the scope of the invention and the appended claims.

Having thus described my invention, I claim:

1. A hoisting device adapted to be installed upon a boat, comprising standards secured to the boat, sockets formed in the upper ends of the standards, spring retaining elements arranged adjacent the sockets to cover the opposite sides thereof, and a rod adapted to be inserted within the sockets.
2. A hoisting apparatus adapted to be installed upon a boat, comprising standards adapted to be connected with the boat near the ends thereof, a pair of sockets carried by the upper end of each standard and disposed upon the opposite sides thereof, leaf springs connected with the end of the sockets and adapted to cover the open sides thereof, a rod adapted to contact with the leaf springs and adapted to be forced into the sockets, and retractile coil springs connected in the standards.
3. A hoisting device adapted to be installed upon a boat, comprising standards adapted to be connected with the boat near the ends thereof, a pair of sockets carried by the upper end of each standard and disposed upon the opposite sides thereof, leaf springs connected with the ends of the sockets and adapted to cover the open sides

thereof, and a rod adapted to contact with the leaf springs and adapted to be forced into the sockets.

4. A hoisting apparatus adapted to be installed upon a boat, comprising standards adapted to be connected with the boat near the ends thereof, a socket carried by the upper end of each standard, leaf springs connected with the ends of the socket and adapted to cover the open side thereof, a rod adapted to contact with the leaf springs and adapted to be forced into the sockets, and retractile coil springs connected in the standards.

5. A hoisting apparatus adapted to be installed upon a boat, comprising standards adapted to be connected with the boat near the ends thereof, a pair of sockets carried by the upper end of each standard and disposed upon the opposite sides thereof and stationary with relation thereto, a rod adapted to be inserted in the sockets, and yielding means to prevent the improper removal of the rod from the sockets.

In testimony whereof I affix my signature in presence of two witnesses.

OTTO CARLSON.
